UNITED STATES PATENT OFFICE

ISAAC LEVY, OF BROOKLYN, NEW YORK, ASSIGNOR TO METROPOLITAN-COLUMBIA MFG. CO., INC., A CORPORATION OF NEW YORK

SHADE HOLDER

Application filed June 8, 1929. Serial No. 369,328.

The present invention relates to shade holders of the type employed in supporting shades, globes, and the like, from sheet metal supports.

5 The present invention contemplates an improved form of shade holder made entirely out of stamped parts and capable of easy manipulation to secure or release a shade or globe. The structure contemplated by the 10 present invention is one which is capable of inexpensive manufacture and easy assembly and which operates efficiently to hold the shade or globe in place. It is preferably characterized by an absence of threaded or 15 tapped parts.

More specifically, the invention contemplates the employment of a member adapted to be swung on a vertical axis to place a shade supporting finger in position to support the 20 shade or to place it in the position to permit lowering the shade. This swinging member is securely held in shade supporting position due to the shape given the parts and their 25 resiliency.

25 Another object of the invention is to provide a shade holder capable of inexpensive construction which compensates for variations in size of shade.

The accompanying drawings show, for purposes of illustrating the present invention, one of the many possible embodiments in which it may take form, together with a slightly modified form of construction, it being understood that the drawings are illustrative of the invention rather than limiting the same.

In these drawings:

Figure 1 is a side elevational view of a shade supported in a shade holder;

40 Figure 2 is a sectional view taken on the line 2—2 of Figure 1, the shade engaging lever being in position to disengage the shade;

45 Figure 3 is an enlarged fragmentary sectional view similar to Figure 2 showing the adjustable shade engaging lever in full lines in shade engaging position and in dotted lines in the shade disengaging position;

Figure 4 is a fragmentary elevational view of a fixed shade engaging device; and

50 Figure 5 is a sectional view taken approxi-

mately on the line 5—5 of Figure 1 but showing a slightly modified form of construction.

In these drawings, a sheet metal body or canopy is indicated at 10. This body or canopy is the ordinary type and has a depending shade receiving skirt 11 of the proper size to receive the lip or bead 12 of a shade. It is customary to support shades of this type at three points, two of which may be fixed or relatively fixed, while the third point of support is adjustable so as to release the shade.

As indicated in Figures 2 and 4, the substantially fixed shade engaging devices are shown at 13, 13 in the form of strips of sheet metal. These strips are of considerably 65 heavier gauge than that of the metal employed in the body 10. The strips are riveted or otherwise secured to the skirt as indicated at 14. These shade engaging members have portions indicated at 15 which are spaced 70 some distance inside the skirt. The free ends 16 of these members are normally spaced a slight distance from the skirt of the shade supporting body. These comparatively stiff strips are adapted to enter in underneath the 75 bead or lip of the shade or other device and will afford two points of suspension. They are somewhat resilient, however, and are capable of being bent to accommodate shades of different sizes. They are normally manufactured to be spaced to accommodate the 80 smaller size shades and are bent outwardly when an oversize shade is inserted.

The adjustable shade engaging device is in the form of a bent lever 20 having two portions 21 and 22 at substantially right angles to one another. This lever passes through a vertical slot 23 in the skirt 11 of the fixture canopy. The member 20 has as here shown upwardly and downwardly extending pintles or bearing forming extensions 24 and 25 which rest against the inner surface of the skirt of the fixture canopy. These extensions or pintles act as bearings and prevent the member 20 from passing entirely through the 95 slot 23.

The shade receiving skirt 11 also carries a comparatively stiff bridging member 26 riveted at its ends to the skirt as indicated at 27. This bridging member in the form 100

shown in Figures 1, 2 and 3 has a centrally located slot 28 considerably larger than the opening 23 in the shade receiving skirt. This slot is adapted to accommodate the inner end 5 22 of the swinging lever 20. The width of the pintles 24 is preferably made somewhat greater than the normal space between the skirt 11 and the bridging member 26. By making the pintles in this manner, it will be 10 apparent that either the bridging member or the shade receiving skirt or both of these parts will be sprung or flexed somewhat out of its normal position when the lever is swung to the shade receiving position, and that when 15 the lever is moved to the shade disengaging position the parts will spring toward one another. This flexing of the parts is indicated by the dotted and full line positions of parts shown in Figure 3. The pintles are cut at 20 an angle as indicated so that there is a slight over-the-center movement of the parts, when the portion of the lever 21 is adjacent the outside of the skirt. This over-the-center movement insures that the resiliency of the 25 parts will hold the lever in shade engaging position. The bridging member 26 is sufficiently close to the skirt of the fixture body so as not to interfere with the lowering of the shade when it is disengaged and as will be apparent from Figure 3, the inner end 22 of the lever will be housed within the slot 28 when in shade disengaging position.

In the modified form of construction shown in Figure 5, the lever 30 is made very 35 much the same as the lever previously described. The bridging member, however, as indicated at 31 is merely a strap placed underneath the shade supporting lever 30. This swinging lever 30 has a downwardly extending bearing forming extension 32 carried between the bridging member 31 and the skirt of the fixture canopy, preferably adapted to 40 flex the parts as above described.

The forms of shade support herein 45 described are all made of sheet metal stampings, and are capable of very cheap manufacture. They are characterized by the entire absence of threaded or tapped parts and hence may be assembled without threading of parts. The 50 entire assemblage of the parts shown in Figure 3 may be held together by riveting or soldering the bridging member to the shade receiving skirt and this operation holds the swinging lever in position. The lever is 55 small and inconspicuous when the fixture is hung, but is, however, readily accessible for disengaging the shade.

It is obvious that the invention may be 60 embodied in many forms and constructions within the scope of the claims, and I wish it to be understood that the particular form and modification shown are but a few of the many forms. Various modifications and 65 changes being possible, I do not otherwise

limit myself in any way with respect thereto.

I claim:

1. A shade holder comprising a sheet metal body having a downwardly extending, shade-receiving skirt, the skirt having an opening 70 therein, a bridging member secured to the skirt on opposite sides of the opening and adjacent the inside of the skirt so as to permit insertion or removal of the shade without interference, and a swinging shade supporting lever passing through the opening, the outer end of the lever being accessible for swinging the inner end of the lever into or out of shade engaging position, the lever having a bearing forming extension interposed between the bridging member and the skirt for holding the swinging lever in position.

2. A shade holder as claimed in claim 1, wherein the bridging member is underneath 85 the lever and the upper inner end of the lever is provided with a curved surface to engage the shade.

3. A shade holder comprising a sheet metal body having a downwardly extending, shade-receiving skirt, the skirt having a vertical slot 90 therein, a bridging member secured to the skirt on opposite sides of the opening and adjacent the inside of the skirt so as to permit insertion or removal of the shade without interference, and a swinging sheet metal shade supporting lever passing through the slot, the sheet metal lever being bent to form an outer end which is accessible for swinging the inner end into or out of shade engaging 100 position, the lever having a bearing forming extension interposed between the bridging member and the skirt for holding the swinging lever in position.

4. A shade holder comprising a sheet metal body having a downwardly extending, shade-receiving skirt, the skirt having an opening 105 therein, a bridging member secured to the skirt on opposite sides of the opening and adjacent the inside of the skirt so as to permit insertion or removal of the shade without interference, and a swinging shade supporting lever passing through the opening, the outer end of the lever being accessible for swinging the inner end of the lever into or out of shade engaging position, the lever having a non-circular, bearing-forming extension interposed between the bridging member and the skirt for holding the swinging lever in position, the bearing-forming extension flexing the sheet metal parts when the lever is shifted from one position to the other so that the lever is held in the position to which it is shifted.

5. A shade holder comprising a sheet metal body having a downwardly extending, shade-receiving skirt, the skirt having an opening 115 therein, a bridging member secured to the skirt on opposite sides of the opening and adjacent the inside of the skirt so 120

as to permit insertion or removal of the shade without interference, and a swinging shade supporting lever passing through the opening, the outer end of the lever being accessible for swinging the inner end of the lever into or out of shade engaging position, the inner end of the lever, when in shade disengaging position being above the bridging member and substantially in the plane of the bridging member, the lever having a bearing-forming extension interposed between the bridging member and the skirt for holding the swinging lever in position.

6. A shade holder comprising a sheet metal body having a downwardly extending, shade-receiving skirt, the skirt having a narrow vertical slot therein, a bridging member secured to the skirt on opposite sides of the opening and adjacent the inside of the skirt so as to permit insertion or removal of the shade without interference, the bridging member having a larger slot opposite the slot in the skirt, and a swinging sheet metal shade supporting lever passing through the slot in the skirt, the outer end of the lever being accessible for swinging the inner end of the lever into or out of shade engaging position, the lever having a bearing-forming extensions interposed between the bridging member and the skirt for holding the swinging lever in position, the inner end of the lever when in the shade disengaging position being accommodated by the opening in the bridging member.

7. A shade holder comprising a sheet metal body having a depending skirt to receive a shade lip, the skirt having a vertical slot, an apertured bridging member secured to the inside of the skirt on opposite sides of the slot, and spaced closely to the skirt, and a swinging shade supporting lever passing through the slot and the aperture in the bridging member, the lever having extensions between the bridging member and skirt acting as bearing pintles for the lever.

8. A shade holder comprising a member having a sheet metal skirt to receive a shade lip, a bent shade supporting lever passing through a slot in the skirt and having an outer grip portion disposed adjacent the skirt when the inner end of the lever is in shade supporting position and moved away from the skirt to release the shade, the lever having a bearing forming extension, and a sheet metal bridging strip carried by the skirt and bearing on the extension, the extension being non-circular to flex the sheet metal parts when the lever is shifted, the lever being thereby held in position to which it is shifted.

ISAAC LEVY.
